UNITED STATES PATENT OFFICE.

JOHN H. MOSS, OF ANGOLA, INDIANA, ASSIGNOR OF ONE-HALF TO CHARLES S. WHITWORTH AND ONE-HALF TO CHARLES C. BOGLE, BOTH OF CEDAR FALLS, IOWA.

GATE.

1,112,081.

Specification of Letters Patent. Patented Sept. 29, 1914.

Application filed May 29, 1913. Serial No. 770,708.

To all whom it may concern:

Be it known that I, JOHN H. MOSS, citizen of the United States, residing at Angola, in the county of Steuben and State of Indiana, have invented certain new and useful Improvements in Gates, of which the following is a specification.

This invention relates to improvements in gates, more particularly to the class of farm gates wherein provision is made for elevating the gate to open the same, and has for one of its objects to simplify and improve the construction and increase the efficiency and utility of devices of this character.

Another object of the invention is to provide a gate constructed wholly of metal and principally of gas or steam piping and so coupled and balanced that the gate will automatically tilt upwardly when released, and which may be lowered into closed position by the exercise of a relatively small amount of force.

With these and other objects in view the invention consists in certain novel features of construction as hereinafter shown and described and then specifically pointed out in the claim, and in the drawings illustrative of the preferred embodiment of the invention.

Figure 1 is a side elevation of the improved gate in closed position; Fig. 2 is a plain view of the same. Fig. 3 is a section on the line 3—3 of Fig. 1 looking in the direction of the arrow. Fig. 4 is an enlarged perspective view of one of the coupling members between the horizontal and vertical members of the gate.

Corresponding and like parts are referred to in the following description and indicated in all the views of the drawings by the same reference characters.

The improved gate may be constructed of any required size to fit within gateway openings located any distance apart, but is designed more particularly for the larger class of farm gates, and for the purpose of illustration is shown thus applied.

The hinge post is represented conventionally at 10 and the latch post at 11, the posts having the usual fence material 12 connected thereto. The hinge post is provided with the lower hinge members 13 of the usual construction, while the latch post

is provided with a latch housing 14 as shown.

The gate is formed with the upper rail member 15 and the lower rail member 16 preferably constructed of tubing such as gas or steam piping.

The upper rail member 15 is provided with a T coupling 17 intermediate its ends, while the lower rail member 16 is provided with a similar T coupling 18. The coupling 17 is provided with spaced ears 19 while the coupling 18 is provided with similar ears 20. Pivoted at its ends at 21—22 between the ears 19—20 is a section of gas piping 23, the gas piping thus forming a swinging connection between the rails 15—16.

At the hinge end of the rail 15 a clip device 24 is secured by a set screw 25, while a similar clip device 26 is connected by a set screw 27 to the lower rail member 16 at its hinge end. Embracing the latch end of the rail member 15 is another clip member 28 secured in position by a set screw 29, while a similar clip member 30 is secured to the latch end of the rail member 16 by a set screw 31. The clip devices 24—26—28—30 are precisely alike and one of the clips is shown in detail in Fig. 4. The clips are provided with depending ears represented conventionally at 32 and embraces the opposite sides of the end members 33—34 of the gate.

The end members of the gate are preferably in the form of flat bars as shown and are pivoted at 35 between the ears of the clips. The centers of the pivots 35 are disposed in alignment longitudinally of the gate with the pivot 21 of the central stay 23, while the pivots 35 of the lower portion of the gate are in longitudinal alignment with the pivot 22. The end member 33 is provided with the receiving hinge members 36—37 which are rigidly coupled to the member 33 as shown at 38—39 and engage over the pintles of the hinge members 13. The end members 33—34 are coupled at suitable intervals by strand wires 40 which may be spaced apart to any required extent, and are generally arranged with the wires nearest the ground spaced at shorter intervals than those at the upper portion of the gate to exclude smaller animals and chickens and the like.

Connected to the terminal member 34 of

the gate is a housing or guideway 41 through which a bolt 42 is mounted to slide, the bolt having an inclined outer end adapted to engage in the latch housing 14 when the gate is depressed and provided with a spring 43 to hold the latch in its outer position or in engagement normally with the housing 14 when the gate is in its lower position.

The lower rail member 16 is provided with a plurality of apertures 44 spaced apart to receive a bolt 45. Engaging the bolt 45 is a U-shaped rod including sides bearing against opposite sides of the gate 46-47. Mounted to swing upon the bolt 15 35 which is employed to secure the clip 24 to the member 33 are curved rods 48-49 to the inner end of which springs 50-51 are coupled at their upper ends, while the lower ends of the springs are coupled respectively to the side portions 46-47 of the U-shaped rod. By this means the springs 50-51 exert a pulling force upon the gate and operate to elevate the same in position shown by dotted lines in Fig. 1 when the 25 latch member 42 is released from the housing 14. By this arrangement the springs are located upon opposite sides of the gate and exert a pulling strain upon the bolt 45 equally from both sides of the gate structure. By adjusting the bolt 45 in the apertures 44 the tension of the spring may be increased or decreased as required, or the spring tightened in event of its becoming weakened by use. It will thus be noted 35 that the pivot 35 which engages the clip 32 performs the two-fold function as a pivot to unite the members 15-32-33 and as a holding device for the connecting members 38-49. The various pivots 21-22-35 40 being maintained constantly at equal distances apart, the gate is not cramped when elevated as the rails 15-16 retain their parallel relation, while the end members 33-34 and the central stay member 23 like-

wise retain their constant parallel relation 45 as illustrated by dotted lines in Fig. 1. The strand wires 40 are passed around the members 33-34 and the terminal twisted around the body of the wire, so that when the gate is elevated the wires will freely bend at their 50 junctures with the end members 33-34, and thus prevent cramping the parts. The members 24-26-28-30 and the members 17-18 are formed respectively from metal, preferably malleable iron, while the end members 55 33-34 are formed from metal bars and the members 16-17-23 are constructed from piping, such as sufficiently enlarged gas or steam piping.

The improved device is simple in construction, can be inexpensively manufactured, is strong and durable and of few parts, and is not liable to get out of order while in use.

Having thus described the invention, what is claimed as new is:

A gate including a frame formed of upper and lower longitudinal members and end members, clips engaging said longitudinal members and including spaced side portions bearing upon opposite sides of said end members, pivot devices extending through the sides of said clips and likewise through the portions of the end members and braced thereby, connecting members swinging upon the upper pivot at the hinge end of the 75 gate and at opposite sides of the same, a spring coupled to each of said connecting members, a stop carried by the lower longitudinal member of said gate, and a rod bent into U-shape and engaging at its bend 80 with a stop and coupled at its terminals respectively to said springs.

It testimony whereof I affix my signature in presence of two witnesses.

JOHN H. MOSS. [L. S.]
